PROCESS FOR SOLVENT EXTRACTION OF
HYDROCARBON OILSDavid R. Merrill, Long Beach, Calif., assignor to
Union Oil Company of California, Los Angeles,
Calif., a corporation of California

Application December 12, 1933, Serial No. 702,015

9 Claims. (Cl. 196—13)

This invention relates to a process for the treatment of petroleum with selective solvents.

In the production of lubricating oil for internal combustion motors, turbines, and other machinery, it is highly desirable to obtain a product which exhibits a low temperature viscosity susceptibility, a low Conradson carbon residue value, a high stability towards sunlight and a low oxidation value.

10 The aromatic, naphthenic and olefinic hydrocarbons present in crude lubricating oil fractions are undesirable because they do not possess these desired characteristics. The more paraffinic hydrocarbons present in crude lubricating oil fractions are the most desirable materials to be employed as lubricants. These compounds are more highly saturated hence, from a chemical standpoint, they are rather inactive and exhibit less tendency towards the formation of undesirable 15 resinous or sludge forming constituents on contact with air at elevated temperatures. Furthermore, these compounds exhibit a low temperature viscosity susceptibility. In other words, they exhibit a minimum change in viscosity for a given change 20 in temperature. Furthermore, these highly saturated hydrocarbons are relatively stable to sunlight, exhibiting little tendency toward discoloration or sludge formation. When I use the term "paraffinic hydrocarbons" I mean those compounds which are present in petroleum having the aforementioned characteristics and which are liquid at ordinary temperatures. This group of hydrocarbons does not include those compounds present which are usually solid or semisolid at ordinary 25 temperature and which are known as "wax" or "petrolatum". As a matter of convenience hereafter, I will refer to the undesirable constituents, such as olefinic, naphthenic and/or aromatic hydrocarbons as the "non-paraffinic" 30 constituents of petroleum.

40 A further indication of the purity of a lubricating oil is its viscosity gravity constant. This constant is an index of the paraffinic or naphthenicity of an oil. A high value represents a high degree of naphthenicity while low values indicate relatively greater paraffinicity. Lubricating oils from natural crudes range from about 45 0.903 viscosity gravity constant for an extreme Gulf Coast type to 0.807 for an extreme Pennsylvania type, or even beyond. The viscosity gravity constant referred to in this application has been determined by the method employed by Hill and Cates as set forth in the Journal of Industrial and Engineering Chemistry, vol. 20, page 641, of 50 55 1928.

In the production of lubricating oil from crude petroleum residues or distillates, it is becoming conventional in the art to separate the desirable paraffinic hydrocarbons from the undesirable olefinic, naphthenic and/or aromatic compounds by 5 the use of solvents which selectively dissolve the undesirable hydrocarbons but which exhibit only a very limited solvent power for the desirable paraffinic hydrocarbons.

A number of selective solvents for this purpose 10 have been found; for example, it has been shown that such materials as liquid sulphur dioxide, beta beta dichlorethyl ether, ortho chloraniline, nitrobenzene, aniline and furfural are highly selective as solvents for the non-paraffinic hydrocarbons. 15 When these relatively heavy solvents are commingled with petroleum or petroleum fractions under the proper conditions of temperature, the undesirable non-paraffinic hydrocarbons pass into solution to a greater or less extent but the desirable paraffinic hydrocarbons remain largely undissolved. The solution of undesirable hydrocarbons and solvent settles to the bottom of the container and forms what is known as an extract phase. The relatively light paraffinic hydrocarbons rise to the top of the vessel and form a raffinate phase. These phases are then readily 20 separable by ordinary decantation means. The raffinate phase is usually found to contain a small quantity of the selective solvent and the extract 25 phase ordinarily contains a relatively large quantity of the solvent. These fractions may be purified by distillation whereby the solvent is distilled away from the hydrocarbon oils.

The quality of raffinate obtainable in a counter- 35 current extraction process with continuous flow depends to a very large extent upon the temperature in the stage from which the final raffinate leaves the system. The higher this temperature is, the better is the quality of the raffinate obtained. For successful operation, however, it is necessary that the conditions in this stage (referred to for convenience as the last stage) should be such that complete miscibility 40 does not occur, for if complete solution occurs 45 in the settling section of this last stage no raffinate can be produced.

The temperature of complete miscibility of all the oil with the solvent (hereinafter termed the miscibility temperature) in any stage is a function of both the average composition of the oil in the stage, including the oil in both phases, and the proportion of total solvent to total oil in the stage. In producing a high quality final raffinate from a stock containing a limited quan- 50 55

5 tity of such raffinate, it is necessary to dissolve and carry away a large proportion of the original feed. In the case of many solvents, such as dichlorethyl ether and, to an even greater extent, liquid sulphur dioxide alone or modified with for example, 30 percent. of benzene, the solubility of the oil in the extract phase even at temperatures within 5° F. or 10° F. of the miscibility temperature is rather limited. In consequence, 10 it is necessary in refining such stocks for the production of low viscosity gravity constant oils to use a large proportion of solvent to feed stock in order to remove in solution from the system the undesirable constituents of the feed.

15 In usual practice, all of the solvent is introduced into the last stage of the system in which the final raffinate is produced. The solvent then passes countercurrently to the flow of raffinate through the various stages of the system until 20 it is removed from the system, carrying with it the non-paraffinic material. The introduction of a large amount of solvent into the last stage has the undesirable effect of lowering the miscibility temperature in this stage and in adjacent stages 25 so that the temperatures at which it is practicable to operate these end stages are materially reduced.

It is an object of my invention to operate the last stages of extraction in which the final raffinate is produced at relatively high temperatures.

It is a further object of my invention to maintain such proportion of solvent to oil in the last stages of extraction in which final raffinate is produced that the mixtures therein are characterized by high miscibility temperatures whereby said extraction may be accomplished at relatively high temperatures.

Referring to the drawings,

40 Fig. 1 is a diagrammatic view of one type of apparatus suitable for carrying out my invention;

Fig. 2 is a diagrammatic view of similar apparatus provided with means for recovering and 45 reusing solvent; and

Fig. 3 is a diagrammatic view of similar apparatus provided with means for rectification.

In the apparatus shown in Fig. 1, oil may be introduced into extraction column 10 from one or 50 both of two sources. Fresh, unextracted oil may enter 10 via line 11 controlled by valve 12 by action of pump 13. Line 11 connects with line 14 and orifice mixer 15 which in turn communicates with column 10 via line 16. If a raffinate 55 produced by a prior solvent extraction is to be treated in column 10, fresh feed is introduced into primary extractor 20 via line 21 controlled by valve 22 by action of pump 23. Fresh selective solvent is introduced into primary extractor 60 20 by action of pump 24 in line 25 controlled by valve 26. Preferably the oil in 20 is subjected to countercurrent extraction by the selective solvent. Low grade extract and the major proportion 65 of the solvent is removed from the primary extractor through line 27 controlled by valve 28. Primary raffinate produced in extractor 20 is removed therefrom through line 30 and valve 31 by pump 32. Line 30 connects with feed line 14.

Extractor 10 is divided into a number of sections 70 35 to 40 by imperforate plates 42. Each section in turn is divided into a mixing zone 43 and a settling zone 44 by plate 45 provided with port 46. Each mixing zone may be provided with an agitator (not shown), if necessary. Column 10 75 is preferably a vertical unit provided with sec-

tions 35 to 40 in descending order. While the feed may be introduced into any of these sections, in practicing my invention, I prefer to introduce the same at the lowest section, for instance section 40. Fresh solvent from tank 50 may be introduced into each section of extractor 10. In some instances, it is not necessary to add fresh solvent to the lower sections such as section 40. High grade raffinate is removed from uppermost section 35 by line 55 controlled by valve 56. Extract is removed from column 10 by line 57 controlled by valve 58.

Fresh solvent for extractor 10 is pumped from tank 50 through line 60 and valve 61 by action of pump 62. That portion of solvent which is 15 then diverted through line 63 enters sections 35, 37 and 39 of column 10 by passage through valves 64 in lines 65 which communicate with orifice mixers 66 and thence by passage through lines 67 into these respective sections. That portion of solvent which is diverted through line 68 enters sections 36 and 38 by passage through valves 69 in lines 70 which communicate with orifice mixers 71 and thence by passage through lines 72 into these respective sections.

When both extractors 10 and 20 are used, the solvent employed in 10 may be the same as that used in 20 or that used in 10 may be a different solvent or may be the same solvent as in 20 modified by the addition of one or more modifying agents to be described. When the same solvent is used in both extractions, valve 26 in line 25 may be closed and the solvent from tank 50 may then pass via lines 60 and 68 through valve 73 and line 74 into extractor 20 for countercurrent extraction therein. When different solvents are employed in the two extractors, valve 73 is closed and the flow of materials proceeds in the manner described above.

As previously described, a fresh supply of solvent 40 may be introduced into each section of column 10. From each section, excluding section 40, the extract phase is removed from settling zones 44 via lines 75 and valves 76 by action of pumps 77. The extract phases from sections 35 45 to 38 pass into the next lower section, respectively, through the orifice mixers with fresh solvent. The extract phase from section 39 passes into section 40 commingled with oil passing through line 14.

From each section, excluding section 35, the raffinate is removed from settling zones 44 via lines 80 and valves 81 by action of pumps 82. The raffinate is then intermingled in the next upper section respectively, with fresh solvent and 55 with extract phase from an upper section. Raffinate from section 36 is intermingled only with fresh solvent prior to passage into section 35.

In the above described apparatus, the solvent is introduced into an upper or primary section, 60 for example 36, an intermediate or secondary section such as 37 and a lower or tertiary section such as 38. The oil is introduced into the lower or tertiary section. Extraction takes place in all sections and the extract phase from the upper 65 section is commingled in the intermediate or secondary section with the raffinate produced in the lower section. Raffinate from the intermediate section travels to the upper section and extract from the intermediate section passes to the lower 70 section.

Due to the general similarity of the various hydrocarbon components of mineral oil fraction such as lubricating oils, solubilities of the undesirable, non-paraffinic fractions and of the de- 75

sirable paraffinic fractions in a selective solvent usually differ only in degree and there is, therefore, a tendency for desirable, high grade paraffinic oil to be carried away with the extract resulting in a loss in the yield of paraffinic fractions obtained. In other words, in a phase separation of extract and raffinate fractions from mineral oil employing a selective solvent, an equilibrium of paraffinic components as well as non-paraffinic components is established between the phases. Consequently, some of the desirable paraffinic fraction is found in the extract instead of in the raffinate.

Because of the magnitude of the partition coefficient of paraffinic constituents between the raffinate and extract phases in section 36, the presence of the highly paraffinic raffinate therein results in substantial proportions of the paraffinic components passing into the extract phase. By intermixing the less paraffinic raffinate from section 38 with the extract and solvent from 36 containing a relatively high proportion of paraffinic materials and causing phase separation in section 37, at least a portion of the paraffinic fractions will pass from the extract into the raffinate.

By contacting an extract-solvent mixture from an upper section of the tower with a raffinate from a lower section, a re-distribution of paraffinic fractions takes place. The extract-solvent mixture contains so large a proportion of paraffinic hydrocarbons and the raffinate from a lower section relatively contains so small a proportion of these hydrocarbons that when said extract and said raffinate are mingled in the presence of the solvent, sufficient paraffinic fractions pass from the extract to the raffinate to establish equilibrium between the two phases. Also, at the same time, some of the non-paraffinic fractions pass from the raffinate to the extract, resulting in a more paraffinic raffinate and a less paraffinic extract. Consequently, after a succession of such steps the final extract contains the least amount of paraffinic fractions and the final raffinate contains those paraffinic fractions which are normally lost in the extract. The solvent associated with the extract and raffinate can be removed therefrom by usual means such as by distillation.

In the operation of the apparatus shown in Fig. 1, fresh, unextracted oil may enter column 10 via lines 11, 14, and 16 in which case extractor 20 may be disconnected from the system by closing valves 31 and 73.

When the total amount of solvent for use in column 10 is introduced into top section 35, the introduction of this large amount of solvent into the last stage has the undesirable effect of lowering the miscibility temperature of the extract phase and raffinate phase in this stage and in adjacent stages so that the temperatures at which it is practicable to operate these end stages are materially reduced. As previously stated, the higher the temperature at which the final raffinate leaves the system, the better is the quality of the raffinate obtained. By distributing the total amount of solvent used in column 10 by separately introducing regulated quantities thereof into sections 35 to 39, the proportion of solvent to oil in the later stages is not excessive and the undesirably large reduction in miscibility temperatures in these later stages is also avoided. In some cases it may be sufficient to introduce solvent into alternate stages or merely into a number of the intermediate stages.

The amount of solvent introduced in the last stage, for instance section 35, is preferably that giving the highest miscibility temperature in this stage when oil of the desired quality is being produced. With constant quality of oil feed to 5 a stage, the total proportion of solvent to oil for the maximum miscibility temperature will vary, depending upon the solvent employed but will usually be not far from the proportions of 100 to 200 volume percent. of solvent, based on the 10 oil feed to that stage. As previously stated the introduction of the solvent is preferably distributed by separate entrance into a number of the sections. When the solvent employed in column 10 is a mixture comprising 70% liquid 15 sulphur dioxide and 30% benzene, the temperature may successively increase from 80° F. in section 40 to 130° F. in section 35.

In the operation of the apparatus shown in Fig. 1, the oil which enters column 10 may be a 20 primary raffinate from extractor 20 in which case valve 31 is open and valve 12 is closed. When the same solvent used in column 10 is also employed in preliminary extractor 20, valve 73 25 is open, valve 26 is closed and oil is introduced into 20 via line 21 in the manner described above. In that case, using the above described liquid sulphur dioxide-benzene mixture, the temperature at which the low grade extract is removed 30 via line 27 may be 20° F. while the primary raffinate produced in the upper part of the extractor 20 may be at 40° F. The primary raffinate may enter column 10 at 85° F. The temperature in 10 may successively increase from 85° F. in section 35 to 130° F. in section 35.

In some instances it may be desired to use a different solvent in column 10 from that employed in extractor 20 or a modified solvent may be used in 10. For example, a hydrocarbon mixture may first be extracted with one of the pure 40 selective solvents set forth above and then the raffinate so produced may be re-treated with one of these solvents modified by carbon bisulphide, xylene, benzene, toluene, carbon tetrachloride, 45 ethers, tetrachlor-ethane or the like. By substantially increasing the solvent power or ease of miscibility of the treating agent, it is possible to fractionate the raffinate obtained after extraction with the pure solvent into a further extract of lower solubility than the first extract obtained by the use of said pure solvent and a second raffinate of consequently lower solubility 50 than the first raffinate.

By these operations the oil feed is divided in 55 one general process into three or more fractions of different viscosity-gravity constants. When operating in this manner valve 73 is closed and solvent is introduced into extractor 20 via line 25. For example, when liquid sulphur dioxide 60 is used in 20, low grade extract may be removed at 80° F. via line 27 and primary raffinate may be removed at 130° F. via line 30. This primary raffinate may be introduced into tower 10 at 85° F. when the solvent used in 10 is the above 65 described liquid sulphur dioxide-benzene mixture. In this case, the temperature in 10 may successively increase from 85° F. in section 40 to 130° F. in section 35. The viscosity gravity constants of the oil in various stages of the apparatus may 70 be as follows: 0.88 for the oil entering the system via line 21 connected with extractor 20; 0.97 for the low grade raffinate from the primary extraction exiting via line 27; 0.84 for the primary raffinate passing via line 31 into extractor 10; 75

and 0.80 for the final raffinate issuing from 10 via line 55.

When both extractors 10 and 20 are employed, it is also possible to estimate closely the optimum proportion of solvent to be introduced into the last stage, section 35. Thus, for example, if the yield of desired quality, final raffinate from a certain stock is known to be 30% and that the proportion of solvent to oil for maximum miscibility temperature is 150 volume percent, while the solubility of oil in the extract phase is 15%, the proportion of solvent introduced into the last stage is about 60%, based on the original feed. This is estimated from the fact that in order to obtain 30% of the original feed as final raffinate at the last stage, about 40% of raffinate must flow into it from an adjacent stage and in order to give the desired 150 volume percent. proportion of solvent to oil, 60% of solvent must be used with the 40% of oil.

After thus establishing the optimum amount of solvent to be employed in the last stage, the remainder of the total amount of solvent required to hold in solution those portions of the feed stock which it is necessary to remove may be distributed over the other stages of this part of the system. For example, if 30% of low grade extract is removed via line 27 and 30% of high grade raffinate is produced in the last stage, section 35, there remains 40% of material to be removed in the form of intermediate extract via line 57. If the solubility of this intermediate extract in the solvent employed at the temperature existing in section 40 is about 13%, the total amount of solvent required in this part of the system will be about 300 volume percent., based on the original feed. If 60 volume percent. is introduced at stage 35, there remains 240 volume percent., to be distributed over the next four stages, or about 60 volume percent. per stage. It is not essential that this distribution over the intermediate stages be in equal amount as a greater distribution in either the higher or lower stages can be offset by adjustment of temperature therein. However, excessive introduction of solvent in the higher stages is to be avoided because the miscibility temperature and the practicable operating temperature in these stages is reduced, thereby interfering with the degree of refinement at these intermediate points. With certain oils, the amount of intermediate quality fractions to be removed is very large and in consequence the amount of solvent required to hold these fractions in solution is correspondingly large. In order to reduce the total consumption of solvent when treating such oils, my invention includes the recirculation of a part of the extract phase to operate as the solvent.

In the apparatus shown in Fig. 2, contaminated solvent is recirculated for this purpose. Parts which are alike in Figs. 1 and 2 have been similarly numbered. Fresh solvent from tank 50 may be introduced into a number of sections of column 10, for instance sections 35, 36, and 37, in order to obtain a high miscibility temperature in the upper sections as previously described.

To recover solvent for reuse, a portion of the intermediate extract phase issuing from column 10 is forced by pump 100 through line 57 into cooler 101 wherein the solvent power of the solvent in the extract phase is reduced by cooling sufficiently to cause phase separation in separator 103 to which the mixture passes via 102. The remaining intermediate extract is drawn off through line 109 and valve 114. An intermediate oil fraction, insoluble in the cooled mixture, is

removed via line 104 and valve 105. The recovered solvent which under preferred temperature conditions in cooler 101 may be contaminated with 3% or less of oil is removed from separator 103 via line 106 and valve 107 by pump 108. The stream of contaminated solvent may then be divided and part is passed via line 110 and valve 111 for intermixture with extract phase from section 38 and raffinate phase from section 40 prior to phase separation in section 39.

Another part of the contaminated solvent may pass into sections 38 and 40 via lines 106, 112, 113 and valve 115 and thence via line 116 and valve 117, orifice mixer 71 and line 72 and via line 118 controlled by valve 119, orifice mixer 15 and line 15 16.

If desired, by opening valve 120 in line 113, the contaminated solvent may be used as the selective solvent in primary extractor 20. In this event, valve 114 in line 109 may be closed so that all the extract phase from 10 will be subjected to treatment for recovery of contaminated solvent. In extractor 20, the contaminated solvent may either be used alone or in intermixture with other solvent entering therein via line 25 in the manner above described.

Another part of the contaminated solvent may pass via lines 106 and 112 through valve 122 into heater 123 where its solvent power is increased by raising its temperature prior to passage through line 124 for intermixture with the primary raffinate issuing from extractor 20 via line 30. The combined flow passes through line 125, orifice mixer 126 and line 127 into separator 130 where phase separation takes place. Extract phase is removed via line 131 controlled by valve 132. Raffinate phase is forced through line 133 and valve 134 by pump 135 into line 118 for intermixture with extract phase from section 39 of column 10 prior to phase separation in section 40 in the above described manner.

As an example of the operation of the apparatus shown in Fig. 2 employing liquid sulphur dioxide in extractor 20, the low grade extract may be removed via line 27 at 80° F. while the primary raffinate may be drawn off at 130° F. Employing the above mentioned mixture of 70% liquid sulphur dioxide and 30% benzene in column 10, the temperature therein may successively increase from 85° F. in section 40 to 130° F. in section 35. Separator 103 may be maintained at 20° F. and separator 130 may be maintained at 85° F. By operating in the above described manner, the successive, controlled introduction of solvent into each stage creates mixtures characterized by high miscibility temperatures whereby phase separation can take place at desirable, relatively high temperatures. Also, an economy of solvent is effected by the return of contaminated solvent.

As previously stated, the contaminated solvent recovered from extractor 10 may be used as the solvent in extractor 20. In that case, the temperature in 10 may successively increase from 80° F. in section 40 to 130° F. in section 35, using the above described liquid sulphur dioxide-benzene mixture. The temperatures in extractor 20 and separators 103 and 130 may all be about 20° F.

When employing the contaminated solvent from separator 103 as the solvent for extraction in 20, the total quantity of solvent employed is preferably restricted to that required for solution of the low grade extract from the feed stock removed via line 27. Thus, for example, if 30% of such oil is to be dissolved and the attainable concentration of this oil in the extract phase in extraction of the 75

feed stock at the low temperature required to give an extract of the desired high viscosity gravity constant is 15%, the amount of solvent required would be 200 volume percent, based on the feed.

5 As previously stated, for the production of a 30% yield of final raffinate, 60 volume percent, is a typical amount of solvent to be introduced into section 35. Therefore, there remains 140 volume percent, to be introduced in the other sections of 10 column 10 and the total requirement of solvent for removal of intermediate grade extract via line 57 is made up by recirculation, for example, of 200 volume percent, of recovered solvent into the intermediate sections. The amount of recirculated 15 solvent will normally be larger than the amount of fresh solvent which would be required because of the presence of residual oil due to the incompleteness of rejection in separator 103 at readily attainable temperatures.

20 My invention may also be combined with rectification during solvent extraction, for example, in the manner shown in Fig. 3 in which parts similar to those described for Figs. 1 and 2 are given the same numbers. As previously described, solvent 25 introduced into column 10 from tank 50 may be apportioned between sections 35 to 38 whereby the mixtures in the last sections are characterized by high miscibility temperatures. Part of the intermediate extract issuing through line 57 is 30 cooled in cooler 101 sufficiently to cause phase separation in 103. The remainder exits through line 109 and valve 114. The raffinate thus produced in separator 103 passes through line 150 and valve 151 by action of pump 152. Part of the raffinate may be removed from the system via 35 line 153 controlled by valve 154.

The remaining raffinate from 103 is mixed with extract phase from section 39 and passes via line 155 into orifice mixer 15 and via line 16 into rectifying section 40 wherein it becomes enriched in high grade components. Loss of such high grade components in the intermediate grade extract is thus reduced.

Part of the extract phase in separator 103 comprising solvent contaminated with oil passes 45 through line 106 and can be removed via valve 156 while the rest travels through valve 101 and pump 108 into heater 123 where its temperature is raised sufficiently to increase its solvent power. The contaminated solvent then travels via line 160 and valve 161 into admixture with primary raffinate passing through line 30 from extractor 20. The mixture continues to pass through line 30 and intermingles with extract phase from section 50 38 and raffinate phase from section 40 before passage into section 39.

If it is desired to use the contaminated oil as the solvent in extractor 20, part of the stream in line 160 may be diverted through line 162 and 55 valve 163. In this event valves 114 and 156 may be closed so that all the extract phase from 10 will be subjected to treatment for recovery of contaminated solvent. In extractor 20, this contaminated solvent may be used alone or with fresh solvent entering via line 25.

As an example of the operation of Fig. 3, employing the above described liquid sulphur dioxide-benzene mixture in column 10, the temperature in section 40 may be 85° F. while the temperature in the upper part of the column may be progressively higher, for instance from 95° F. in section 39 to 130° F. in section 35. Separator 103 may be at 20° F. When using contaminated solvent from separator 103 as solvent in extractor 20, 60 the low grade extract may be removed via line 27

at 20° F. and the primary raffinate may be removed via line 30 at 40° F.

It should be understood that these temperatures are merely by way of illustration and that they may be varied for other stocks and solvents. 5 Furthermore, the number of stages shown in the figures is to be considered merely typical for these general conditions and may be varied as described. Thus, more than one rectification stage 10 may be employed and the number of extraction stages may be increased or decreased as is found desirable in any particular circumstance.

I claim:

1. A process for the separation of paraffinic and non-paraffinic fractions from an oil containing the same which comprises introducing only sufficient selective solvent at a primary extraction stage to produce a mixture characterized by a high miscibility temperature, introducing said oil at a tertiary extraction stage, removing raffinate 20 from the primary stage and extract phase from the tertiary stage and at a secondary stage commingling extract phase from the primary stage, raffinate from the tertiary stage and additional selective solvent. 25

2. A process for the separation of paraffinic and non-paraffinic fractions from an oil containing the same which comprises introducing only sufficient selective solvent at a primary extraction stage to produce a mixture characterized by a high miscibility temperature, introducing said oil at a tertiary extraction stage, removing raffinate from the primary stage and extract phase from the tertiary stage and at a secondary stage commingling extract phase from the primary stage, raffinate from the tertiary stage and additional selective solvent, separating extract phase and raffinate from said secondary stage, introducing said last mentioned raffinate into the primary stage and said last mentioned extract phase into 40 the tertiary stage. 35

3. A process as in claim 2 in which the temperature in the primary stage is higher than the temperature in the secondary stage and the temperature in the secondary stage is higher than the temperature in the tertiary stage. 45

4. A process for the separation of paraffinic and non-paraffinic fractions from an oil containing the same which comprises extracting said oil with a selective solvent, separating a primary raffinate insoluble in said solvent from a low grade extract soluble therein, introducing only sufficient selective solvent into a primary stage of a second extraction system to produce a mixture characterized by a high miscibility temperature, introducing said primary raffinate into the tertiary stage of said second extraction system, removing a raffinate from the primary stage and an extract from the tertiary stage, at a secondary stage of said second extraction system commingling extract phase from the primary stage, raffinate from the tertiary stage and additional solvent, separating extract phase and raffinate at said secondary stage and introducing said last mentioned raffinate into the primary stage and said last mentioned extract into said tertiary stage. 55 60 65

5. A process for the separation of paraffinic and non-paraffinic fractions from an oil containing the same which comprises flowing said oil and a selective solvent countercurrently, introducing only sufficient selective solvent into that zone from which final raffinate is removed to produce a mixture characterized by a high miscibility temperature, removing extract phase from said countercurrent extraction, cooling said extract phase to 70 75

- separate a raffinate insoluble therein from contaminated solvent and introducing said contaminated solvent into said countercurrent extraction at an intermediate point.
- 5 6. A process for the separation of paraffinic and non-paraffinic fractions from an oil containing the same which comprises introducing only sufficient selective solvent at a primary extraction stage to produce a mixture characterized by
- 10 a high miscibility temperature, introducing said oil at a tertiary extraction stage, removing raffinate from the primary stage and extract phase from the tertiary stage, cooling said last mentioned extract phase to separate a raffinate insoluble therein from contaminated solvent and at a secondary stage commingling said contaminated solvent with extract phase from the primary stage and with raffinate from the tertiary stage.
- 15 7. A process for the separation of paraffinic and non-paraffinic fractions from an oil containing the same which comprises introducing only sufficient selective solvent at a primary extraction stage to produce a mixture characterized by a high miscibility temperature, introducing additional selective solvent at an intermediate point in said countercurrent extraction, removing extract phase from said extraction, cooling said extract phase to separate an insoluble oil fraction from contaminated solvent and returning said last mentioned insoluble oil fraction into said first mentioned countercurrent extraction.
- 20 8. A process for the separation of paraffinic and non-paraffinic fractions from an oil containing the same which comprises flowing said oil and a selective solvent countercurrently, introducing only sufficient selective solvent into that zone from which final raffinate is removed to produce a mixture characterized by a high miscibility temperature, introducing additional selective solvent at an intermediate point in said countercurrent extraction, removing extract phase from said extraction, cooling said extract phase to separate an insoluble oil fraction from contaminated solvent and returning said last mentioned insoluble oil fraction into said first mentioned countercurrent extraction.
- 25 9. A process for the separation of paraffinic and non-paraffinic fractions from an oil containing the same which comprises introducing only sufficient selective solvent at a primary extraction stage to produce a mixture characterized by a high miscibility temperature, introducing said oil at a secondary extraction stage with additional solvent, introducing raffinate from the secondary stage into the primary stage, removing raffinate from the primary stage, introducing extract phase from the primary stage into the secondary stage, introducing extract phase from the secondary stage into a tertiary stage, introducing raffinate from said tertiary stage into said secondary stage, cooling extract from said tertiary stage to separate an insoluble oil fraction from contaminated solvent and returning said last mentioned insoluble oil fraction into said tertiary stage.
